HANDLE FOR A SKILLET OR SIMILAR ARTICLE

Frederick W. Becker, Mansfield, Ohio, assignor to Westinghouse Electric Corporation, a corporation of Pennsylvania

Application July 9, 1956, Serial No. 42,170

Term of patent 14 years

(Cl. D44—29)

FIG.1.

FIG.2.

FIG.3.

FIG.5.

FIG.4.

Fig. 1 is a perspective of a handle for a skillet or similar article, showing the new design;

Fig. 2 is an enlarged perspective;

Fig. 3 is a top plan;

Fig. 4 is a side elevation; and

Fig. 5 is an end elevation.

The dominant features of this design reside in the full-line portions on the drawing, and the broken line skillet and knob are for illustrative purposes.

The opposite side of the handle not in view in Fig. 2 is substantially similar in appearance to the side shown.

I claim:

The ornamental design for a handle for a skillet or similar article, substantially as shown and described.
